UNITED STATES PATENT OFFICE.

LUDWIG GLASER, OF BERLIN, GERMANY.

BALLAST DEVICE FOR NERNST LAMPS.

No. 820,489.

Specification of Letters Patent.

Patented May 15, 1906.

Application filed June 8, 1905. Serial No. 264,263.

To all whom it may concern:

Be it known that I, LUDWIG GLASER, a subject of the Duke of Saxe-Coburg-Gotha, residing at Berlin, Germany, have invented 5 certain new and useful Improvements in Ballast Devices for Nernst Lamps, of which the following is a specification.

It has not heretofore been feasible to use second-class conductors of large cross-section 10 for lamp-filaments because of the lack of a suitable ballast resistance. The iron wires which have proved successful as choking or reducing resistances for lamps with small filaments do not begin to glow quick enough for 15 filaments of larger cross-section. It is only possible to use these large filaments at high current by including in the circuit a regulating resistance; but this arrangement makes the lamps very expensive, especially as this 20 regulating apparatus must be self-acting in order not to be dependent on the skill of the operator.

According to the following invention it is possible to utilize with these large glowers 25 resistances made of iron wires or other suitable material with a high-temperature coefficient, provided the resistance is divided into parallel parts only one of which is constantly connected to the glower and the other or others 30 of which may be connected in parallel with the first at the proper time through any suitable automatic device. The resistances may be located in an evacuated vessel or in one filled with indifferent gas and so arranged 35 that when the first resistance has heated the vessel to a suitable temperature the other resistance or resistances will be automatically put in circuit.

The accompanying drawing shows my im- 40 proved arrangement.

The supply-wires 1 and 2 conduct current through the bottom of the evacuated vessel and are connected, respectively, to the wires 3 and 4 within the vessel. Between 3 and 45 4 an iron wire 5 is wound in spiral form. A second wire 6 is connected from 4 to the short wire 7, which is fastened to a glass ball 8, melted to the wire 3 and serving to insulate the wire 7 from the wire 3. A spiral spring 9, 50 commonly known as a "Breguett's" spring, is carried on the wire 7 and is of such a nature that when heated sufficiently it will touch the contact-wire 10, connected to 3, but when cool will interrupt this contact immediately. 55 The wire 10 may be made of platinum, nickel, or other suitable material.

For operating a two-ampere lamp the dimensions of the wires 5 and 6 may be so proportioned that one carries 1.5 amperes and the other .5 amperes. When the lamp has 60 been switched on and while the glower 11 is becoming more conductive, the current which goes through the glower will flow at first only through the resistance 5. This resistance 65 will begin to glow immediately, as it is constructed for a weaker strength of current than the glower, and thus will delay for a short time any increase of current above 1.5 amperes. In the meantime the whole vessel will be heated from resistance 5, and the 70 spring 9 will be turned to establish contact with the wire 10. This operation throws the resistance 6 in shunt with the resistance 5, thus raising the total current to two amperes. The resistance 6 when thrown in circuit is 75 brought rapidly to a red heat and then begins to choke, as will be readily understood.

It is very important to prevent any substantial vibration of the spring 9, as the temperature at which the contact is established 80 and also the time interval between the switching on of the lamp and the establishment of the multiple circuit should be always constant. For this reason a stop 12, of insulated wire, is arranged on the side of the spring 85 opposite the wire 10. By the distance of the two wires 10 and 12 the above-mentioned interval can be regulated. The regulation of the resistance may be effected by any of the well-known methods. 90

For electric lamps of very high current a suitable division of the resistances may be made when necessary, so that several iron wires are arranged in parallel, one of which is constantly switched on, but the others of 95 which may be switched on one after the other as needed through the instrumentality of a plurality of Breguett's springs of different sizes and having different movement-spaces.

What I claim as new, and desire to secure 100 by Letters Patent of the United States, is—

1. A ballast for second-class conductors comprising a resistance having a high-temperature coefficient, a second resistance operatively related thereto, and automatic 105 means for connecting said second resistance in shunt with said first resistance after the latter has attained a suitable temperature.

2. A ballast device for a conductor of the second class including as a part thereof a resistance having a high-temperature coefficient, and automatic means for connecting 110

said resistance in circuit with said second-class conductor after current begins to flow through said conductor.

3. A ballast device for a conductor of the second class including as a part thereof a high-resistance filament, and thermostatic means for electrically connecting said filament to said conductor and for disconnecting it therefrom.
4. A ballast device for electrical apparatus comprising a filament having a high-temperature coefficient, a second filament operatively related thereto, and means operated by heat from one of said filaments for connecting the two filaments in parallel.
5. A ballast for conductors of the second class comprising an evacuated chamber, a high-resistance filament therein, means for

supplying current thereto, a second filament therein, and automatic means in said chamber for connecting said filaments in parallel after one of said filaments has been heated by the flow of current therethrough.

6. A ballast for electric apparatus comprising an evacuated chamber, a high-resistance filament therein, a second resistance operatively related thereto, and a heat-actuated spiral for connecting said resistances in parallel when said chamber has reached a predetermined temperature.

In witness whereof I have hereunto set my hand this 22d day of May, 1905.

LUDWIG GLASER.
